UNITED STATES PATENT OFFICE.

JOHN B. HEINOLD, OF KEARNEY, NEW JERSEY.

BUCKLE.

SPECIFICATION forming part of Letters Patent No. 730,120, dated June 2, 1903.

Application filed February 28, 1903. Serial No. 145,569. (No model.)

To all whom it may concern:

Be it known that I, JOHN B. HEINOLD, a citizen of the United States, residing at Kearney, in the county of Hudson and State of New Jersey, have invented a new and useful Buckle, of which the following is a specification.

This invention relates to improvements in buckles, and has for its object to combine with an ordinary buckle a pad or other suitable lock which may be applied without decreasing the strength of the strap or materially increasing the weight or expense of the buckle; and the invention consists in certain novel features of the construction, as herein-after shown and described, and specified in the claims.

In the drawings illustrative of the invention, in which corresponding parts are denoted by like designating characters, Figure 1 is a perspective view of the device applied. Fig. 2 is a perspective view of the improved buckle detached.

Many forms of receptacles—such as telescopes, valises, hold-alls or extension-satchels, some forms of trunks, hampers, and the like—upon which binding-straps are employed and also articles secured by shawl-straps dependence is frequently had to the straps only for the security of the contents, and the improvement which is the subject of the present invention is designed to secure such straps by providing means whereby a pad or other lock may be attached to the buckles and so constructed that it does not interfere with the ordinary use of the buckle or weaken or otherwise affect the straps.

The buckle-frame (represented at 10) will be of the ordinary form and provided with the outer transverse bar 11 and rear transverse bar 12, as shown. Extending from the outer bar 11 is a lug 14, relatively thin in cross-section and disposed longitudinally of the buckle-frame and transversely of the bar and provided with a relatively large transverse aperture 15, adapted to receive the bolt 16 of a padlock 17.

Movably connected to the rear bar 12 is a tongue 18, provided with a relatively elongated aperture 19, adapted to engage the lug 14 and be locked in position thereon by the lock-bolt 16, between the bolt and the bar 14, as indicated.

gated aperture 19, adapted to engage the lug 14 and be locked in position thereon by the lock-bolt 16, between the bolt and the bar 14, as indicated.

By forming the lug 14 relatively thin the aperture 19 in the tongue 18 can be formed correspondingly narrow, so that it will not be necessary to materially increase the width of the tongue to receive its aperture. Hence the presence of the connecting means does not require the aperture for the tongue in the strap to be materially increased. Thus the straps used in connection with the improved buckle will not be weakened, while at the same time they will be supported in precisely the same manner and capable of all the adjustments of the ordinary buckle and strap. All that is required is to form the tongue-apertures in the straps a trifle longer than ordinary, but not larger transversely, as the yielding nature of the strap material will readily permit the passage of the slightly-widened portion of the tongue opposite the aperture 19 without affecting the texture of the strap. The slight elongation of the tongue-apertures in the straps, it is obvious, will not lessen their tensile strength.

The improved device may be attached to any of the ordinary forms of buckle-frame or to any special form of frame employing a movable buckle-tongue.

Having thus described my invention, what I claim is—

1. A buckle provided with a lug disposed upon its forward bar in longitudinal alignment with the buckle-frame and having a transverse aperture providing means for the attachment of a padlock-bolt, and a tongue movably connected to the buckle-frame in the rear of said apertured lug and having a longitudinal aperture in its free end adapted to engage said lug between its aperture and the buckle-frame, substantially as described.

2. A buckle-frame formed with transverse bars at its opposite ends and with a lug extending from one of said bars and disposed in longitudinal alignment with the buckle-frame and provided with a transverse aper-

ture for a lock-bolt, and a tongue rotatively connected to the other of said transverse bars and having an aperture in its free end longitudinally of the tongue adapted to engage 5 said lug between its aperture and the buckle-frame, substantially as described.

In testimony that I claim the foregoing as

my own I have hereto affixed my signature in the presence of two witnesses.

JOHN B. HEINOLD.
